UNITED STATES PATENT OFFICE.

ISAAC SNOW, OF LAWRENCE, MASSACHUSETTS.

SHUTTLE AND BOBBIN GUARD.

Application filed October 31, 1923. Serial No. 671,877.

This invention relates to looms and is particularly adapted for weft replenishing looms wherein a bobbin is forced into spring jaws in a shuttle which has no spindle.

Substantially all looms include a lay-beam on which is the race for the shuttle. This lay-beam carries a reed on the top of which is a reed cap. Extending out from the reed cap over the lay-beam is a shuttle guard, the purpose of which is to prevent the shuttle from flying upward out of the loom as it sometimes has a tendency to do.

With a weft replenishing loom it occasionally happens that when the bobbin is forced by the hammer, into the jaws of the shuttle, it does not function accurately and the tip sticks up over the top of the shuttle in a position where it is likely to strike the warp.

When this occurs, the projecting bobbin may cause a smash, or rip out a great many warp threads as it is thrown along the lay-beam.

The purpose of this invention is to provide a shuttle guard which also serves as a bobbin guard. In my device, if the tip of the bobbin projects above the top of the shuttle and into the warp it will strike one of a plurality of transverse members forming a part of the guard and will be stopped, thereby stopping the shuttle before much, if any, damage is done.

The warp is usually so elastic that no threads are broken but in any event, only a few are broken.

In the drawings, Fig. 1 is a side elevation showing part of a lay-beam with a reed and reed cap attached, together with the warp, shuttle, harnesses, etc.

Fig. 2 is a front elevation showing part of the lay-beam with my guard attached and the bobbin projecting up from a shuttle.

Fig. 3 is an enlarged front elevation showing one type of my guard.

Fig. 4 is a bottom view of Fig. 3.

Fig. 5 is a bottom view of another modification of my guard.

Fig. 6 is a sectional elevation on line 7-7 of Fig. 5.

Fig. 7 is a front elevation of Fig. 5.

Fig. 8 is a front elevation of a simple form of my guard adjusted so that its fins project down through the warp.

Fig. 9 is a front elevation of another modification.

Fig. 10 is a bottom view of the guard shown in Fig. 9.

Fig. 11 is a bottom view of another modification.

Fig. 12 is a plan view of another modification.

Fig. 13 is a side elevation showing my device with an old type of shuttle guard.

In the drawings A¹ and A² represent the harnesses of a loom through which the warp threads W¹ and W² pass from the warp L through the reed C to the cloth O.

B is the lay-beam horizontally along the top of which is the race 11 for the shuttle 70 S which carries the filling P through the warp.

The reed C is carried by the lay beam and supports reed cap 10 in a well known manner. This reed cap 10 does not extend entirely over the shuttle race 11 nor over the width of the shuttle when in the race.

In Figs. 1, 2, 3, 4, H represents one form of my device consisting of a strip of sheet metal which extends horizontally along the lay-beam over the lay and is fastened along one edge to the reed cap. I show this fastening means as ears 30 in which are vertical slots 31 through which pass adjusting screws 33 by which it can be raised or lowered.

This guard may conveniently be constructed by forming fins 32 by bending or crimping the material cross-wise or transversely. Preferably also at the bottom ends 90 of these fins or crimps, the metal is upset as at 34 so that when the tip of the bobbin strikes, it will not slip off side-ways.

In Figs. 5, 6, 7, I show a modified construction in which is used a metal strip 60 which is preferably bent longitudinally at a slight angle along its inner edge 63 and at a right angle 64 at outer edge. To form the downwardly projecting transverse members or fins 62, the metal is cut out as shown in 61 and bent at a right angle so that these fins project downwardly from the guard. The bent outer edge 64, prevents the bobbin tip from slipping off sideways.

In Fig. 10, I show a similar construction with the guard M wherein the edges are not bent but the fins 50 are cut out from the metal at 51 and the guard M is so adjusted that these fins as shown in Fig. 8 stick down through the top warp threads W¹. As these are thin and the warp is continually moving along, no harm is done to it and the fins

can be adjusted so as to be very close to the shuttle.

In Fig. 9 my guard 41 is bent or waved to form transverse members 40.

5 In Fig. 11 I show a guard formed like a ladder with the side members 60, and cross members 61, which project downward.

In Fig. 12 I show a guard R which consists of a flat piece of metal with members

10 70 the edges of which are bent down and which project in towards the reed cap 10 to which the guard is fastened by arms 71. With this construction, either the yarn mass

15 on bobbin F, or the tip 20 will strike a member 70 and stop the bobbin and shuttle.

Fig. 13 shows I may use my guard H on a reed cap 10 without removing the old shuttle guard D.

As shown in Figs. 2 and 9, I may use one

20 or more intermediate supports such as 80 of

bracket form riveted at 81 to my guard and having vertical adjusting slots 82 for supporting screws 33 in addition to the end supports.

It is obvious that my guard could be 25 made in a single length or in several lengths and that it could be used on a loom in which hand threading shuttles, having bobbin spindles, were used.

I claim:

The combination with a weft replenishing loom having a reed cap carried by its lay-beam, of a shuttle and bobbin guard consisting of a horizontal metal strip having spaced transverse fins projecting downward therefrom and fastened at one edge to the reed cap so as to extend horizontally along the lay-beam over the lay and having its other edge bent downward. 30 35

ISAAC SNOW.
